UNITED STATES PATENT OFFICE.

GEORGIA C. ORMSBY, OF OAKLAND, CALIFORNIA.

DESIGN FOR A DOLL.

47,496.

Specification for Design.

Patented June 22, 1915.

Application filed April 10, 1915. Serial No. 20,583. Term of patent 7 years.

To all whom it may concern:

Be it known that I, GEORGIA C. ORMSBY, a citizen of the United States, residing at Oakland, in the county of Alameda and State of California, have invented a new, original, and ornamental Design for Dolls, of which the following is a specification, reference being had to the accompanying drawing, forming part thereof.

The figure is a perspective view of a doll, showing my new design.

I claim:

The ornamental design for a doll, as shown.

GEORGIA C. ORMSBY.
